UNITED STATES PATENT OFFICE.

GEORGE M. BACON, OF SALT LAKE CITY, UTAH, ASSIGNOR TO BACON MULTIPLIER, INCORPORATED, OF SALT LAKE CITY, UTAH, A CORPORATION OF UTAH.

COMPUTING MACHINE.

Application filed September 9, 1921. Serial No. 499,451.

To all whom it may concern:

Be it known that I, GEORGE M. BACON, a citizen of the United States, and resident of Salt Lake City, county of Salt Lake, and State of Utah, have invented certain new and useful Improvements in Computing Machines, of which the following is a specification.

My improvement relates more particularly to improvements in the register wheel and transfer mechanism and the mechanism for restoring the register wheels to zero, of my improved machine, as more particularly shown and described in my pending application, Ser. No. 429,107, filed December 8, 1920, for multiplying machines.

While the physical embodiment of the machine shown and described in the above application has been giving satisfactory results in operation, it has been found desirable to improve the construction in various details in order to facilitate assembling the machine more readily and to simplify and improve the construction, and thereby reduce friction and improve the action.

In the register wheel and transfer mechanism shown and described in my prior application, the line of shafts leading to the register wheels comprises an intermediate section rotatably supported in axial alignment with two other shafts including the register wheel shafts and a clutch mechanism was interposed for disconnecting the intermediate shafts from the register wheel shafts for returning the register wheels to zero. The thrust of the spring for the clutch and the lack of rigidity in the jointed shafts not only complicate the mechanism, but increased the friction in the machine.

Furthermore, in the construction shown in the prior application, the gear connections in the transfer mechanism associated with the register wheels of the product and the total product register wheels while similar in construction and operation, were not so designed as to be duplicates so that corresponding gears of one group or unit are identical with those of the other unit. This has been done in the construction herein described, thereby cheapening manufacture and facilitating assembling of the parts.

In my present improvement, it will be seen that the clutches referred to have been eliminated and the register wheel and driving shafts are made up of but two shafts

both of which are supported in ample bearings so that greater rigidity is secured and, as previously stated, the various gears and pinions making up the driving connections between the two sections of the shafts, and forming the interconnected transfer mechanism, have been so designed that those used in the total products unit are substantially duplicates of those used in the products unit.

As shown and described in my application, above referred to, the register wheels are rotated twice for each rotation of the driving shafts, operated by the differential gears, and intermediate planetary pinions and gears are utilized for connecting the two shafts together and giving the required difference in speed of rotation. The relative size of the gears and pinions making up the planetary gears for doubling the speed of rotation of the register wheel may be varied more or less, but it is well known that the best results may be obtained when the meshing gears are more nearly the same size. There will be less friction and less lateral thrust than would be the case with a large gear driving a small pinion.

Therefore, one object of my present improvement is to so proportion the pitch and diameter of the intermeshing gears and pinions as to reduce to a minimum the friction and thrust which might affect the case of operation or life of the machine. In this case, it has been found that for the best results the ideal relation between the intermediate gears and pinions should be in the ratio of the square root of two to one. It is somewhat difficult to obtain this exact ratio, but by a proper selection of the pitch and number of teeth, I have worked out a very close approximation to the ideal ratio above referred to.

In my improved multiplying machine, alternate register wheels or dials of both the products and total products units rotate in opposite directions and in my prior application, the mechanism shown for restoring the dials to zero comprise mutilated pinions and two oppositely disposed mutilated racks for cooperation with the mutilated pinions for rotating adjacent register wheel dials in opposite directions when restoring them to zero. Another object, therefore, of my improved construction, is to simplify this mechanism and provide for separating

2
the interconnected transfer gearing so that all of the register wheel shafts may be rotated in the same direction for restoring them to zero, thus requiring but a single mutilated rack for cooperation with the mutilated gears. This improved construction further eliminates the necessity for rotating the clearing pull and improves and simplifies the construction as well as requiring less power and rendering the operation more uniform.

In accomplishing this feature of my improved machine, it will be noted that a particularly novel construction has been devised in which a separation of the interconnected transfer gearing is accomplished by simultaneously moving all of the multi-toothed Geneva wheels out of operative relation with the single toothed Geneva members, so that both may be rotated independently in restoring the register wheels to zero.

Another feature of my present improvement relates to means for preventing overthrow of the register wheels when returning them to zero. It is obvious that when restoring the register wheels to zero, the speed or rotation of the register wheels may be considerable and the inertia may cause the wheels to overthrow after the rack reaches the flattened or mutilated portion of the respective pinions. To obviate this objection, I have in my present improvement, devised a simple and novel mechanism for preventing such overthrow of the register wheels and for accurately stopping them at the zero point.

The accompanying drawings will serve to illustrate the details of my present improvements and only such parts of the complete machine as are necessary to properly show the improvement are here shown, for reference may be had to the complete showing of the machine in my prior application, Ser. No. 429,107, hereinbefore referred to.

In the accompanying drawings, Fig. 1 represents a vertical longitudinal section through the products dials and also through the total products dials; Fig. 2 is a transverse broken section, substantially on the line 2-2 of Fig. 3; showing the movable frame carrying the Geneva wheels; Fig. 3 is a front view partially in section showing the clearing pull bar; Fig. 4 is an enlarged view of the differential gearing of the product dials, looking toward the front from the line 4-4 of Fig. 1; Fig. 5 shows the Geneva single toothed member and the associated Geneva wheel of one of the total product register wheels, the view being taken on the line 5-5 of Fig. 1; Fig. 6 is a vertical transverse broken section, showing parts of the gear mechanism of the total products dials; Fig. 7 is a broken transverse vertical section showing details of the mechanism of the products dials; Fig. 8 is a sectional detail

substantially on the line 8-8 of Fig. 1, showing the clearing rack and the mechanism for preventing overthrow when restoring the register wheels to zero, and Fig. 9 is a top plan view of the mechanism of Fig. 8, and also shows the clearing pull rod.

Referring to the drawings, and particularly to Fig. 1 thereof, it will be seen that the product register wheels and transfer mechanism are substantially duplicated in the total products register wheels and transfer mechanism and, therefore, it will not be necessary to fully describe the two units separately. The mechanism will be described in connection with the products dials or register wheels and the corresponding parts in the total products unit will be given the same number, with the exponent "a."

From Fig. 1, it will be seen that the gear mechanism of the products register dials may be assembled and mounted as a unit, the mechanism supported between angle plates 1 and 2, which extend transversely of the machine and may be secured to the side plates thereof by screws or otherwise, as may be desired. Each products register wheel or dial 3 is secured to the forward end of the shaft 4, which is supported in a transversely extending plate or bar 5, as shown in Fig. 1 of the drawings. The shaft 4 passes rearward through the angle plate 1, and has a bearing therein. The rear end of the shaft 4 at 6 is turned down and enters a socket in the forward end of the driving shaft 7 which passes through and has a bearing in the angle plate 2. The rear end of the shaft 7 may be supported in the bearing brackets of the differential wheels, substantially as shown in my prior application, No. 429,107, hereinbefore referred to. It will thus be seen that the two shafts 4 and 7 are in axial alignment and are both rigidly supported, so that there is little likelihood of cramping or disarrangement of the cooperating mechanisms.

The shaft 7, at its rear end carries the pinion 8, which is slidably mounted thereon and adapted to mesh with the differential gears when slid longitudinally of the shaft, as shown in my prior application. Preferably, the pinion 8 is secured to the end of a tubular barrel 9, provided with longitudinal slots 10, cooperating with a pin 11, extending through the shaft 7 into the slots 10, as indicated in Fig. 1 of the drawings. In this manner the sliding connections between the shaft 7 and the pinion 8 is placed at a greater distance from the axis of the shaft, and therefore, will not be greatly affected by wear or lost motion. The rear end of the barrel 9 is provided with an annular groove at 12 and a notched disc or wheel 13, is connected therewith, the notches of which are adapted to cooperate with a pin 14 projecting from the angle plate 2, for locating

and holding the pinion 8 in proper meshing relation with the differential wheels, as shown and described in my prior application. The lever arm 15 carrying the roller 16, which operates in the annular groove 13 is provided for selectively positioning the pinion 8, according to the multiplicand digits, as shown and described in my prior application.

10 The rotation of the driving shaft 7 is communicated both to the products dials and to the total products dials and for this purpose, the inner end of the shaft is provided with a gear 17, which may preferably be 15 connected by a tubular shaft or hub 18 with a spur gear 19, the two gears in the products unit being secured to the shaft 7 by a pin 20, as seen in Fig. 1 of the drawings. The gear 19 meshes with the corresponding gear 19^a, 20 of the total products unit which through the tubular shaft or hub 18^a rotates the corresponding gear 17^a, (see Fig. 1). The gear 17 meshes with a pinion 21 secured to or integral with a gear 22, both rotatably 25 mounted on a pin or stud 23, secured to and projecting laterally from a large spur gear 24, which is rotatably mounted upon the shaft 4. Between the large spur gear 24 and the gear 17 a pinion 25 is mounted upon the end 30 of the shaft 4 and held to rotate therewith by means of the key indicated at 26. In order that the action of the planetary gears and pinions may be more evenly balanced, it is preferable to have two sets of the planetary pinions and gears 21-22 mounted on the large gear 24 at diametrically opposite points, as will be seen from the drawings.

As previously indicated, small intermeshing planetary gears of this type, should be 40 properly proportioned, in order to obtain the best operating results. In my machine, the relation between the interconnecting gears between the shafts 4 and 7 are so related that the shafts 4, carrying the register wheels 45 or product dials, are rotated twice for each rotation of the driving shafts 7, or of the tubular shaft 18 and gear 19, which corresponds with the similar parts 18^a and 19^a of the total product dials.

50 I have found by careful calculation and experiment that for back gearing of this character, in which the shaft 4 is rotated twice for each rotation of the shaft 7, the ideal ratio between the intermeshing gears 55 and pinions should be approximately as the square root of two to one. In utilizing standard pitch gears, it is somewhat difficult to obtain this exact ratio, nevertheless, I have worked out a very close approximation thereto by making the gears substantially as follows:—The gears 17 are forty-two pitch with twenty-four teeth and mesh with the pinions 21, which are of forty-two pitch with eighteen teeth. The gears 22, which 60 rotate with the pinions 21 are of forty pitch

with twenty-four teeth and drive the pinions 25, which are of forty pitch with sixteen teeth. It is found that these relations approximate very closely to the ideal ratio above indicated and so split up or 70 divided the work of each gear and pinion, that the wear and friction is reduced to a minimum, while, at the same time, the proper relations are maintained between centers of the various gears and pinions. 75

The large gears 24, which support the planetary pinions 21 and 22 are rotatably mounted upon the shafts 4, but are ordinarily held against rotation by the engagement therewith of pinions 27, secured to shafts 28, 80 which shafts also carry the Geneva wheels 29. The latter, in the present instance, are provided with four teeth or operating notches for cooperation with the single tooth Geneva members 30, which are secured to the 85 shafts 4 by means of the pins 31, as will be seen in Fig. 1 of the drawings. The Geneva members 30 are provided with laterally projecting annular flanges 32, which cooperate with the dwell portions of the Geneva wheels 90 29, thereby preventing rotation of the pinions 27 and the associated large gears 24, except where the flanges 32 are interrupted and the single operating tooth or pin 33 is provided, as indicated in Figs. 5 and 7 of 95 the drawings.

It will be observed that the construction and interconnection of the register wheels and transfer mechanism, so far as the mode of operation is concerned, is substantially identical with that described in my pending application hereinbefore referred to. However, in the former construction, the corresponding annular flanges 32 were made wider and the single toothed Geneva members 30 were keyed to the shafts and slidably mounted thereon, so that they could be moved to open the clutches while the Geneva wheels remained in contact with the flanges 32. This construction permitted the register 100 wheels to be returned to zero, but it was necessary to rotate adjacent wheels in opposite directions. The presence of the clutches and their springs not only added to the complication of the mechanism but increased the 105 work of operating the machine. 110

In the present improvement, it is proposed to simplify the construction and reduce the friction as well as provide for rotating all of the register wheels in the same direction when restoring them to zero. For this purpose, the shafts 28, carrying the pinions 27 and star or Geneva wheels 29, are all rotatably mounted in a separate movable frame, comprising side bars 34 and 35, which may be rigidly secured together by tubular members 36, substantially as indicated in Fig. 2 of the drawings. The frame 34-36 is slidably supported transversely of the machine, 125 between the angle plates 1 and 2, by means 130

4

of pin and slot connections therebetween. As indicated in Figs. 2 and 3 of the drawings, the pins 37 at the right end are secured in the angle plates 1 and 2 respectively, and project through the slots 38 in the movable frame members 34 and 35, while at the left end, the pins 39 are secured in the frame members 34 and 35 and project through slots 40 in the angle plates 1 and 2. It will be observed that the slots 38 and 40 are elongated in the arc of a circle, so that when the frame 34-35 is moved toward the left, as indicated in Figs. 2 and 3 of the drawings, the Geneva wheels 29 will be moved out of the field of the corresponding single tooth Geneva members 30, while the pinions 27 will move circumferentially of and remain in mesh with the corresponding large gears 24. In the normal position, 15 with the frame 34-35-36 toward the right, as indicated in Fig. 2, the Geneva wheels will be in operative engagement with the corresponding flanges 32 of the Geneva members 30, so as to be in position to transfer 20 the tens when the register wheels are rotated in the ordinary manner. For the purpose of holding it in and returning the frame 34-35-36 to normal position, a spring 41 is preferably provided, one end of which is 25 secured to a pin 42 projecting from one edge of the frame bar 34, the opposite end being secured to a pin 43 secured in the frame plate 1, as indicated in Fig. 2 of the drawings.

When it is desired to reset the register wheels or product dials to zero, this 30 may be done by simply moving the frame 34-35-36 toward the left, as shown in Figs. 2 and 3 of the drawings and then rotating the register wheel shafts 4 until the 35 register wheels are brought to zero. For the purpose of restoring the register wheels to zero, the product dials register is provided with a pull bar 44, which is provided with a suitable knob or pull, as shown in 40 my previous application, but in the present instance, the bar 44 is merely slidably mounted transversely of the machine. The bar 44 is provided with a cam projection at 45, adapted to cooperate with the short arm 50 46 of a bell-crank lever, pivoted at 47 on angle plate 1, the long arm 48 of which projects downward, as indicated in Fig. 3 of the drawings, into position to engage the end of one of the pins 39 projecting through 55 the plate 1.

For restoring the register wheels to zero, each of the register wheel shafts 4 is provided with a mutilated pinion 49 secured to the respective shafts by suitable pins 50, 60 which may project beyond the pinions and are utilized for preventing overthrow of the register wheels when restoring them to zero as will be more particularly described hereinafter. The pinions 49 are preferably elongated as shown in Fig. 1 of the drawings,

and about half the widths thereof are retained with all the teeth, as indicated at the left in Fig. 8 of the drawings, to serve as the toothed members for cooperation with detent springs 51, which are adapted to locate and hold the respective register wheels in proper registration with the eight openings in the machine. The front halves of the pinions 49 are mutilated at 52 by removing two teeth, as indicated in Fig. 8 of the drawings, and a suitably mutilated rack 53 is mounted transversely thereof for cooperation with the mutilated pinions to restore the register wheels to zero, by reciprocating the rack. The rack 53 is mutilated 70 by removing a few of the teeth at 54, so that when the rack is in the normal position indicated in Fig. 8, the pinions 49 may be freely rotated with the register wheels. The mutilated rack 53 is slidably supported by 75 means of pin and slot connections between the rack and front plate 1, in any suitable manner. Preferably a pin 55 at the left end of the rack 53 projects through the elongated horizontal slot 56 in the plate 1 and 80 through a short slot 57, in the clearing pull rod 44, as indicated in Fig. 9 of the drawings. The end of the pin 55 may be threaded and provided with a nut 58 for holding the parts in operating relation. A suitable 85 spring, such as shown in my prior application, may be provided for holding the rack 53 toward the left, which is the normal position, as shown in Figs. 8 and 9 of the drawings. It has previously been explained that 90 the clearing pull bar 44, by means of the cam 45 is adapted to first separate the Geneva wheels and then the register wheels can be rotated by the rack 53 to restore them to zero. In order that this may be done, 95 the bar 44, by means of the short slot 57 is permitted a sufficient amount of movement for the cam 45 to operate before the bar picks up the pin 55 and moves the rack 53.

The clearing pull rod 44 is slidably supported by the pin 55 and by means of a pin or stud 59 operating in a slot 60, as indicated in Fig. 3 of the drawings, the slot 60 being of sufficient length to allow for pulling out the rack 53 far enough to restore the 110 register wheels to zero. A suitable spring 61 is provided for restoring the clearing bar to normal position and full stroke mechanism, such as shown and described in my prior application, may be employed in connection with the clearing pull if so desired.

It has been pointed out that there is a possibility of overthrow of the register wheels when the rack 53 reaches the flat or mutilated portions 52 of the pinions 49, particularly when the clearing pull is operated at high speed. This is likely to cause reengagement of the pinions 49 with the racks and, to avoid this, it is desirable to provide suitable means for preventing overthrow. 125 130

In the present instance, this is accomplished in a simple manner by providing the radially extending pins 50, which are so placed as to rotate immediately back of and out of the field of the rack 53. For cooperation with the pins 50, when restoring the register wheels to zero, a notched plate 62 is slidably mounted between the rack 53 and a retaining plate 63 which may be secured to the angle plate 1, by means of screws 64, the retaining plate 63 being held in proper spaced relation therefrom, by suitable collars 65 as indicated in Figs. 8 and 9 of the drawings. The notched plate 62 is provided with 15 slots 66 cooperating with suitable pins 67, projecting from the retaining plate 63, as indicated in Fig. 8 of the drawings. The plate 62 is shown in normal position in Fig. 8 of the drawings, and is provided with recesses 68 on the lower edge thereof of sufficient width and depth to permit the free rotation therein of the pins 50 when the plate is in the normal position. If, however, the 20 plate 62 is moved toward the left, the depending tongue portions of the notched plate 62 will be brought into the field of the pins 50 and serve to prevent or stop the rotation of the register wheels already at zero or after they have been rotated to the zero 25 point, by the rack 53. The notched plate 62 is held in the normal position shown in Figs. 8 and 9 of the drawings, by means of a laterally extending lug 69, secured by a pin or screw 70 to the upper edge of the rack 53, at the left end thereof, the lug 69 being adapted to cooperate with a pin 71 projecting upward from the edge of the plate 62. A spring 72 is preferably connected with the pin 71, and to a fixed pin 73, so as to normally urge the plate 62 toward the left, or 30 into position for the plate to intercept the pins 50. Normally the parts will be in the positions shown in Figs. 8 and 9, but it will be understood that when the clearing pull 44 is drawn out to restore the register wheels to zero, the rack 53 will be moved toward the left and by the time the mutilated rack picks up the teeth of the mutilated pinions 49, the spring 72 will have moved the plate 35 62 into the field of the pins 50. The movement of the plate 62 under the action of the spring 72 will be limited by the length of the slot 66 cooperating with the pin 67.

As shown and described in my prior application, the planetary gear mechanism and Geneva wheels are located in two planes so that adjacent mechanisms overlap thereby concentrating the mechanism and getting the register wheels closer together. Both the 40 products and the total products register wheels are arranged in this manner and the construction and operation of both sets of wheels and associated mechanisms is substantially identical, the only difference 45 being that the relation of the gears is re-

versed, so that the pinions 49^a are at the rear ends of the shafts 4^a and the gears 19^a and 17^a, connected by the tubular shafts 18^a, rotate upon the shafts 4. Suitable spacing collars 74 and 74^a are provided for properly 70 spacing the respective gears on the shafts 4 and 4^a.

In the operation of the machine, it will be understood that adjacent shafts 7 are rotated in opposite directions, and, therefore, adjacent register wheels in both the product and total product units are rotated in opposite directions. The transfer of the tens is accomplished by the Geneva members 30, operating the respective Geneva wheels 29 80 each time the corresponding register wheel passes from nine to zero or from zero to nine. After the product has been obtained, the register wheels may be cleared by operating the clearing pull bar 44, which, as previously 85 pointed out, first operates the bell-crank lever 46—48, which moves the Geneva wheel carrying frame 34—35, so as to disconnect the Geneva wheels 29 from the Geneva members 30, after which the pin 55 (see Fig. 9) 90 is picked up by the bar 44, and the clearing rack 53 is moved toward the left. The rack 53 will engage the mutilated pinions 49 of any of the register wheels that are not at zero and rotate them all in the same direction, until the mutilated or flattened portions 52 thereof are brought opposite the teeth of the rack. During the operation the overthrow mechanism comes into operation 95 to prevent the register wheels moving beyond the zero positions, this being accomplished by the engagement of the pins 50 with the tongue-like portions of the notched stop plate 62, as previously described.

It is believed that the relation, which I 105 have worked out between the planetary gears and pinions for approximating the ratio of the square root of two to one is particularly novel and certainly of very great importance in connection with machines of this character, for reducing friction and wear on the parts and, thereby increasing the efficiency of operation. It is also believed that my improved method of separating the interconnecting transfer mechanism, is particularly 110 novel, as is also the mechanism for preventing overthrow of the register wheels when 115 restoring them to zero.

It will be understood, therefore, that in 120 my claims for these improvements, I do not wish to be limited to the specific construction shown and described, for obviously, the details thereof may be modified or varied, without departing from the spirit 125 and scope of the invention.

I claim:—

1. In a computing machine, the combination of a plurality of register wheels, interconnected by transfer mechanism comprising planetary gears and Geneva wheels and 130

their actuators, and means for simultaneously moving all of said Geneva wheels out of engagement with the respective actuators while they remain geared to the planetary gears.

2. In a computing machine, the combination of a plurality of register wheels and transfer mechanism, including a Geneva actuator connected with each register wheel, a plurality of Geneva wheels each geared to the adjacent register wheel of higher denomination and mounted for cooperation with the respective Geneva actuators for transfer of the tens and means for bodily moving all of said Geneva wheels out of operative relation to the respective Geneva actuators, whereby both the Geneva wheels and said actuators may be independently rotated while restoring said register wheels to zero.

3. The mechanism as claimed in claim 2, in which the respective Geneva wheels are geared through intermediate planetary gears with the respective register wheels, so that each Geneva actuator is adapted to transfer the tens to the register wheel of next higher denomination, when said Geneva wheels are in operative relation with the respective actuators, and detents are provided for positioning and holding the respective register wheels in proper registering positions, both when the Geneva wheels are in and when out of operative relation to the Geneva actuators.

4. In a computing machine, the combination of a plurality of register wheels and transfer mechanisms, the latter including planetary gears, a single toothed Geneva actuator connected with each register wheel, a multi-toothed Geneva wheel cooperating with each of said Geneva actuators and geared respectively to the planetary gearing of higher denomination, a common frame in which all of said Geneva wheels are mounted and means for moving said frame as an incident to restoring said register wheels to zero, so as to simultaneously disengage the Geneva wheels from the Geneva actuators while they remain geared to the respective planetary gearing.

5. The mechanism as claimed in claim 4, in which a manually operated pull is provided for moving said frame and the Geneva wheels and means is operated by said pull for restoring said register wheels to zero after said Geneva wheels have been disengaged from the Geneva actuators.

6. In a computing machine of the character described, the combination of a plurality of register wheels, a plurality of interconnected gears for transferring the tens, means for simultaneously disconnecting corresponding portions of the respective transfer gears, means for restoring said register wheel to zero when said transfer gears are so disconnected, and a manual pull for

operating said disconnecting means and the restoring means in succession.

7. The mechanism as claimed in claim 6, in which said intermediate transfer gearing includes a Geneva wheel geared to a large gear which supports planetary gears and the separation of said transfer gearing is effected in a manner to permit independent rotation of the register wheels and said Geneva wheels and planetary gears.

8. In a computing machine of the character described, the combination with a plurality of registering elements and transfer mechanisms, of a single toothed Geneva member secured to each register wheel, a corresponding plurality of Geneva wheels, adapted during the transfer of the tens to be operated by the respective Geneva single toothed members, a movable frame in which all of said Geneva wheels are mounted, means for supporting said frame and permitting sufficient movement thereof to allow for the rotation of said Geneva wheels independently of the single toothed Geneva members, a clearing pull for restoring the register wheels to zero and means operative by said clearing pull for moving said frame when said pull is operated for clearing.

9. The mechanism as claimed in claim 8, in which means is provided for restoring said frame to normal position after the clearing operation of said pull with said Geneva wheels and Geneva members in engagement and for holding them in such engagement during normal operation.

10. In a computing machine of the character described, the combination of a plurality of register wheels and interconnected transfer mechanism, the latter being made separable, a corresponding plurality of mutilated pinions connected with the respective register wheels for restoring them to zero, a single mutilated rack for cooperation with said pinions, means for preventing overthrow of said register wheels when the mutilated portions of said pinions come opposite the rack and the register wheels are at zero, and a clearing pull for separating the separable portions of the transfer mechanisms and for operating said rack after the separation takes place.

11. In a computing machine of the character described, the combination with register wheels and transfer mechanisms, of mutilated pinions connected with the respective register wheels, a single mutilated rack for cooperation with said pinions for restoring the register wheels to zero, a slideable stop plate under the control of said rack and a plurality of stop members associated with the respective register wheels and adapted to cooperate with said stop plate for preventing overthrow of the register wheels when returned to zero by said rack.

12. The mechanism as claimed in claim

11, in which a clearing pull is provided for operating said rack to restore the register wheels to zero and said stop plate is brought into position to intercept said stop members only when said pull is operated to move said rack.

13. In a computing machine of the character described, the combination with register wheels and transfer mechanism, of 10 means for restoring the register wheels to zero, comprising mutilated pinions secured to the respective register wheels and a single mutilated rack movable transversely thereof for rotating all of said pinions in the same 15 direction to restore the register wheels to zero, a corresponding plurality of stop members secured to the respective register wheels and pinions, a stop plate held nor-

mally out of the field of said stop members but adapted to be moved into the field thereof when said rack is operated, means for moving said rack and independent means for moving said stop plate when said rack is moved.

14. The mechanism as claimed in claim 25 13, in which a manually operated clearing pull is provided for operating said rack, and a spring is adapted to move said stop plate in a direction to place it in the field of said stop members, said rack being provided 30 with a lug engaging said plate for moving it in the opposite direction to restore it to normal position out of the field of said stop members.

GEORGE M. BACON.
